UNITED STATES PATENT OFFICE.

MARTIN E. BRIGHAM, OF PHILADELPHIA, PENNSYLVANIA.

OILING DEVICE.

1,106,775.

Specification of Letters Patent.

Patented Aug. 11, 1914.

Application filed December 20, 1909. Serial No. 533,985.

To all whom it may concern:

Be it known that I, MARTIN E. BRIGHAM, a citizen of the United States, and resident of the city and county of Philadelphia, State 5 of Pennsylvania, have invented an Improvement in Oiling Devices, of which the following is a specification.

My invention has reference to oiling devices and consists of certain improvements 10 which are fully set forth in the following specification and shown in the accompanying drawings which form a part thereof.

My invention has reference to that class of oiling devices adapted to engines and machinery where there are a large number of parts which require to be individually oiled, whether the said supply of oil is required to be the same or in different quantity to the 15 respective parts. My improvement is particularly useful in automobiles where the machinery is out of close observation and where the duty on the engine is especially hard and necessitating lubrication which must be amply sufficient to meet the utmost 20 requirements without waste.

The object of my invention is to provide suitable automatic means for supplying lubrication to a plurality of independent portions of one or more machines from a common 25 source of oil supply; and moreover to insure the requisite amount of oil being delivered to each of the parts to be lubricated without regard to the amount of oil delivered to any of the other parts.

My invention has a further object in the economical distribution of the oil, whereby all waste is eliminated and only the exact amount necessary is supplied to the parts to be lubricated for a given amount of work to 35 be done.

My invention consists of certain features of construction by which the above objects are carried out, the said construction being fully described hereinafter and more particularly defined in the claims. These improvements will be better understood by reference to the drawings, in which:

Figure 1 is a rear elevation of an oiling apparatus embodying my invention; Fig. 2 is a front elevation of the same with the oil tank removed; Fig. 3 is a sectional elevation of the distributing device; Fig. 4 is a cross section thereof; Fig. 5 is a perspective view of the eccentric yoke for operating the

pumps; and Fig. 6 is an enlarged sectional elevation of one of the sight feeding devices for controlling the relative amount of oil distributed into each distributing pipe.

2 is a reservoir for the lubricant and may be of any character desired, 3 is a distributing case into which the oil is pumped under pressure by pumps 4, the said pumps being provided with suction pipes 5^a which connect with the oil supply pipe 5 through a cross fitting 5^b. The pump cylinders 4 are each provided at their outer ends with check valves 6 which may be of any suitable character, but preferably of the construction shown in Fig. 3 and screwed into the ends of the pump cylinders. These check valves 6 have the valve pieces 6^a preferably spring pressed upon their seats by coil springs 6^b. Each of the pump cylinders is provided with a plunger 19, said plunger being made tubular and having a valve seat 23 upon which a check valve 24 seats itself under the action of a spring 22, said parts being located within the plungers, as shown in Fig. 3. The plungers are respectively secured to each side of a yoke 18 within the case 3 which is reciprocated by an eccentric 17 formed on a rotating disk 12 arranged within the case 3 and journaled at 13 in bearings in the body of the case and the cover plate 3^a, as shown in Fig. 4. This disk 12 is provided with teeth 14 which are driven by a worm 15, rotated by a shaft 16, and by which the disk is positively rotated at a moderate speed and caused to operate the pumps 4. The shaft may be rotated by any means desired, but is usually connected with some part of the operating machinery to be lubricated. The particular manner of rotating the disk is immaterial. The disk 12 is provided with one or more apertures 20, and on 40 one side, in circular alinement with said apertures the disk is turned true, to form seats 21. These annular seat portions work against the inner face of the case 3, through which there are a plurality of distributing ports 26, said ports arranged in circular form so that the apertures 20 in the disk are brought successively into alinement with the said distributing ports 26. The disk 12 is pressed toward the distributing ports by 45 means of a spring 27, which is put under tension by a screw or other suitable adjusting device 28.

Each of the distributing ports 26 connects with a separate distributing pipe 7 through a sight feed mechanism 29, which may be of any ordinary construction and is preferably provided with the adjusting valve 30. In Fig. 2, fourteen of these distributing pipes and sight feeds are shown arranged in two concentric circular rows, and of course it will be understood that more or less of such distributing outlets may be employed, as desired. By employing sight feeds 29, it is evident that as the oil is delivered to all of the distributing pipes under the same pressure, the amount of oil which actually flows into each distributing pipe may be regulated under sight adjustment by means of the adjusting valves 30. Where the oil is not permitted to fall by gravity but is circulated in the pipes 7 under forced pressure, the sight feeds would not be required, except to know that oil was flowing; and in this case the adjusting valves 30 may be employed without the sight portions, as the oil would flow through the distributing pipes 7 (under the pressure existing within the case) whenever one of the apertures 20 comes in front of the distributing ports 26 and this flow may be regulated by the valves 30. In most cases, however, the distributor may be arranged at a sufficient elevation to insure the oil in the distributing pipes 7 flowing downward by gravity, so that sight feeds would be desirably employed.

31 is a safety valve which is provided with the valve piece 32 closed upon its seat by a spring 33 against the pressure of the oil within the case 3. Any oil which is forced through this safety valve enters a bypass 34 which connects with the cross fitting 40 5^b, and re-circulates to the pumps 4. In this manner, no excessive pressure can be put upon the oil within the case 3, and whatever pressure is intended, is definitely predetermined by the tension of the spring 33. 45 This tension may be adjusted by forming the part 35 of the safety valve adjustable and thereby putting the spring under more or less tension, as desired.

The casing 3 is provided with an air chamber 36, preferably opening from the cap above the worm 15, and a pressure gage 37 may be attached to the air chamber 36 and be located in a suitable position for observation. As the air is sealed above the oil within the air chamber 36, the elasticity of the air is always available for causing a steady and elastic flow of the non-elastic oil, and hence there is very little danger of leakage from hydrostatic pressure. As before stated, should the pressure tend to increase above the predetermined amount by failure of the oil to pass out through the distributing pipes with sufficient speed, the pumps will re-circulate the oil within the case 65 through the bypass 34 and safety valve 31.

If, from any cause, the apparatus for rotating the disk 12 should become deranged, it is evident that there would be no delivery of oil through the distributing pipes, except in case that one of the apertures 20 in the disk should happen to be over one of the distributing ports 26. To overcome this possible contingency, I provide an adjusting screw 38 in the end of one of the bearings 13, which, upon being screwed up, will push the disk away from the case and allow the oil to enter the various distributing ports 26 directly. In this manner, the oiling devices may be operated similar to any ordinary static distributor with sight feeds. 70 This adjustment may be maintained by means of a lock nut 39. 75

I prefer to locate the oil reservoir 2 at a higher elevation than the case 3 so that the oil feeds to the pumps by gravity, said construction being indicated in Fig. 1, but I do not restrict myself to this arrangement as, broadly considered, it is immaterial how the oil reaches the pumps, whether by suction or gravity. 80

While, for convenience and compactness, I have arranged the pumps within the case, it is evident that the operation would be the same if the pumps were arranged otherwise, and moreover, while I employ two pumps, it is evident that one of these may be dispensed with, if so desired, and I therefore do not limit myself to such details. The advantage of using two pumps is that, two single acting pumps accomplish the same result as a 90 double acting pump, and moreover maintain a constant circulation of the oil. 95

I have shown my invention in the form in which I have used it in commercial practice, and while the construction shown is commercially satisfactory and practical, I nevertheless do not limit myself to the details and they may be modified without departing from the invention defined in the claims. 105

Having now described my invention, what I claim as new and desire to secure by Letters Patent, is: 110

1. In an oiling device, the combination of an oil reservoir, a pressure chamber receiving oil from the reservoir, a plurality of distributing pipes leading from the pressure chamber and respectively having ports opening into the interior of the chamber, continuously acting pumping means wholly independent of the oil reservoir for forcing the oil into the chamber under pressure, relief means for maintaining the oil within the chamber under constant pressure, a by-pass from the relief means to the pumping means whereby the oil from the relief means opposes the flow of oil from the reservoir to the chamber except in accordance with the demand for the oil for lubrication, and means common to all of the ports interposed between the said ports and the oil space in 120 125 130

the pressure chamber for intermittently and successively controlling the flow of the oil from the chamber to the plurality of ports without affecting the maintenance of the 5 constant pressure.

2. In an oiling device, the combination of a pressure chamber, a plurality of distributing pipes leading from the chamber and having ports opening into the interior of the 10 chamber, double pumping devices for continuously introducing oil into the chamber for maintaining the oil within the said chamber under constant pressure, and means interposed between the ports and the 15 oil space in the chamber consisting of a rotating disk seating against the ports to close them and having one or more apertures through it adapted to be brought into alignment successively with each of the several 20 ports of the distributing pipes for intermittently permitting the flow of the oil under its constant pressure from the pressure chamber into the distributing pipes.

3. In an oiling device, the combination 25 of an oil reservoir, a pressure chamber, a plurality of distributing pipes leading from the chamber and having ports opening into the interior of the chamber, continuously acting pumping means for introducing oil into the 30 chamber in a continuous manner and for recirculating the excess of oil within the said chamber and without return to the oil reservoir whereby pressure is maintained within the said pressure chamber, a rotating 35 disk seating against the ports to close them and having one or more apertures through it adapted to be brought into alignment successively with each of the several ports of the distributing pipes for intermittently permitting 40 the flow of oil from the pressure chamber into the distributing pipes under pressure, and regulating means in the several distributing pipes for separately controlling the relative amounts of oil passing 45 through the respective distributing pipes.

4. In an oiling device, the combination of an oil reservoir, a pressure chamber, a plurality of distributing pipes leading from the pressure chamber, continuously acting means 50 for permitting an intermittent discharge of oil from the pressure chamber simultaneously into a plurality of the distributing pipes and shifting the discharge successively to different sets of pipes, independent means 55 outside of the pressure chamber for independently controlling the speed of flow of the oil through the respective distributing pipes, a single supply pipe from the reservoir, continuously acting pumping devices 60 for sucking the oil from the supply pipe and discharging it into the pressure chamber, a bypass from the pressure chamber into the suction side of the pumping devices and between them and the supply pipe of the 65 reservoir for recirculating the excess of oil

through the pressure chamber without returning it to the reservoir, and a pressure relief valve in said bypass to govern and maintain constant the pressure within the pressure chamber and under which the oil is 70 fed to the distributing pipes.

5. In an oiling device, the combination of a pressure chamber, a plurality of distributing pipes leading from the chamber and having ports opening into the interior of the 75 chamber, means for maintaining the oil within the chamber under pressure, means interposed between the ports and the oil space in the chamber consisting of a rotating disk seating against the ports to close them and having one or more apertures through it adapted to be brought into alignment successively with the several ports of the distributing pipes for intermittently permitting the flow of the oil from the pressure 80 chamber into the distributing pipes, and means for adjusting the rotating disk to or from the ports on the inside of the case to enable the oil to be discharged from all of the distributing ports simultaneously 85 90 when desired.

6. In an oiling device, the combination of a pressure chamber, a plurality of distributing pipes leading from the chamber and having ports opening into the interior of the 95 chamber, means for maintaining the oil within the chamber under pressure, means interposed between the ports and the oil space in the chamber consisting of a rotating disk seating against the ports to close them and having one or more apertures through it adapted to be brought into alignment successively with the several ports of the distributing pipes for intermittently permitting the flow of the oil from the pressure 100 chamber into the distributing pipes, spring device for pressing the disk into contact with the portion of the case through which the ports extend, and means for adjusting the disk away from the said ports 105 and putting the spring device under compression when it is desired to simultaneously distribute oil from all of the ports. 110

7. In an oiling device, the combination of a pressure chamber, a plurality of distributing pipes leading from the chamber and having ports opening into the interior of the chamber, continuously acting means for maintaining the oil within the chamber under pressure comprising an air chamber 120 in communication with the pressure chamber containing the oil in which air is held under compression together with two pumps alternately acting for forcing oil into the pressure chamber, and a bypass having a 125 spring actuated relief valve opening from the pressure chamber and discharging to the suction side of the pump, means interposed between the ports and the oil space in the chamber consisting of a continuously ro- 130

tating disk seating against the ports to close them and having one or more apertures through it adapted to be brought into alinement successively with the several ports of the distributing pipes for intermittently permitting the flow of the oil from the pressure chamber into the distributing pipes.

8. In an oiling device, the combination of a fixed pressure chamber for the oil, a plurality of distributing pipes leading from said chamber and opening therein through ports, a plate movable over the ports and having one or more passages through which the oil may flow from the interior of the fixed pressure chamber into the distributing ports successively, mechanical devices for continuously moving the plate, an oil reservoir separate from the pressure chamber, two pumps alternately acting for pumping oil from the reservoir into the pressure chamber, and means consisting of a bypass from the pressure chamber to the supply side of each of the pumps and having a pressure relief valve in said by-pass, whereby a constant pressure is maintained in the pressure tank irrespective of the delivery therefrom or the supply thereto from the reservoir.

9. In an oiling device, the combination of a pressure chamber, a plurality of distributing pipes leading from the chamber and having ports opening into the interior of the chamber, continuously acting means for maintaining the oil within the chamber under pressure comprising an air chamber in communication with the pressure chamber containing the oil in which air is held under compression, and two pumps alternately acting for forcing oil into the pressure chamber, a relief device for allowing the re-circulation of the oil by the pump whenever the pressure within the pressure chamber exceeds a predetermined amount, consisting of a safety valve device opening from the pressure chamber and a by-pass pipe leading from the safety valve and connecting with the suction pipe of the pump at the pressure chamber, means interposed between the ports and the oil space in the chamber consisting of a rotating disk seating against the ports to close them and having one or more apertures through it adapted to be brought into alinement successively with the several ports of the distributing pipes for intermittently permitting the flow of the oil from the pressure chamber into the distributing pipes.

10. In an oiling device, the combination of a pressure chamber, a plurality of distributing pipes leading from the chamber and having ports opening into the interior of the chamber, means for maintaining the oil within the chamber under pressure comprising an air chamber in communication with the pressure chamber containing the oil in which air is held under compression, a pump for forcing oil into the pressure chamber,

ber, a relief device for allowing the re-circulation of the oil by the pump whenever the pressure within the pressure chamber exceeds a predetermined amount consisting of a safety valve device opening from the pressure chamber and a by-pass pipe leading from the safety valve and connecting with the suction pipe of the pump, means for adjusting the resistance of the safety valve, an oil reservoir, a pipe leading from the oil reservoir and in communication with the by-pass and pressure chamber, means interposed between the ports and the oil space in the pressure chamber consisting of a rotating disk seating against the ports to close them and having one or more apertures through it adapted to be brought into alinement successively with the several ports of the distributing pipes for intermittently permitting the flow of the oil from the pressure chamber into the distributing pipes.

11. In an oiling device, the combination of a pressure chamber having a plurality of distributing ports for delivering oil to suitable distributing pipes, a rotatable disk journaled within the chamber and having one or more passages through which oil may flow from the chamber into the distributing ports in succession during the rotation of the disk, means to rotate the disk, and a pump operated by the disk to pump oil into the pressure chamber.

12. In an oiling device, the combination of a pressure chamber having a plurality of distributing ports for delivering oil to suitable distributing pipes, a rotatable disk journaled within the chamber and having one or more passages through which oil may flow from the chamber into the distributing ports in succession during the rotation of the disk, two oppositely acting pumps operated by the rotating disk and discharging into the pressure chamber, suction pipes from the two pumps connected with each other, an oil tank, and a pipe leading from the oil tank and discharging into the suction pipes.

13. In an oiling device, the combination of a pressure chamber having a plurality of distributing ports for delivering oil to suitable distributing pipes, a rotatable disk journaled within the chamber and having one or more passages through which oil may flow from the chamber into the distributing ports in succession during the rotation of the disk, two oppositely acting pumps operated by the rotating disk and discharging into the pressure chamber, means to maintain an elastic pressure within the chamber, a relief valve to permit the discharge of oil from the chamber whenever the pressure within the chamber becomes excessive, a by-pass for returning the oil which passes through the relief device again into circulation, suction pipes from the two pumps

connected with each other, an oil tank, and a pipe leading from the oil tank and discharging into the suction pipes.

14. In an oiling device, the combination 5 of an oil reservoir, a pressure chamber, means for maintaining a pressure within the pressure chamber, a plurality of distributing pipes leading from the pressure chamber, a pump to deliver oil from the reservoir into 10 the pressure chamber against the pressure therein, pump actuating devices, a valve device at all times operative from the pump actuating devices and having an orifice of constant area common to all of the distribut-

ing pipes for successively forming a passage for the oil from within the pressure chamber into the distributing pipes, and bypass means whereby the excess of oil discharged from the pressure chamber controls the amount of the supply of oil from the 20 reservoir to the pump.

In testimony of which invention, I hereunto set my hand.

MARTIN E. BRIGHAM.
